(57) **CLAIM**

The ornamental design for a wireless speaker system, as shown and described.

DESCRIPTION

FIG. 1 is a perspective view of a wireless speaker system incorporating our new design, showing a base thereof and a wireless speaker thereof;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is a perspective view of the wireless speaker of the wireless speaker system illustrated in FIG. 1, showing a handle thereof in a second position. The wireless speaker is shown separately for clarity of illustration.
